CLAIM

The ornamental design for a wearable information terminal, as shown and described.

DESCRIPTION

FIG. 1 is a front, right side, bottom perspective view of a wearable information terminal showing our new design; FIG. 2 is a front elevational view thereof; FIG. 3 is a rear elevational view thereof; FIG. 4 is a left side view thereof; FIG. 5 is a right side view thereof; FIG. 6 is a top plan view thereof; FIG. 7 is a bottom plan view thereof; FIG. 8 is a reference front elevational view thereof, showing an example of a used state; and, FIG. 9 is a reference perspective view thereof, with a wristband attached.

The broken line showing of the used state in FIG. 8 and the wristband in FIG. 9 form no part of the claimed design.
